UNITED STATES PATENT OFFICE.

JAMES T. TAYLOR, OF SPRINGFIELD, OHIO, ASSIGNOR TO THE ELWOOD MYERS COMPANY, OF SPRINGFIELD, OHIO, A CORPORATION OF OHIO.

CAN-BODY-MAKING MACHINE.

Application filed February 16, 1921. Serial No. 445,311.

To all whom it may concern:

Be it known that I, JAMES T. TAYLOR, a citizen of the United States, residing at Springfield, in the county of Clark and State 5 of Ohio, have invented certain new and useful Improvements in Can-Body-Making Machines, of which the following is a specification.

This invention relates to improvements 10 in the method of and apparatus for making sheet metal cans; it relating more particularly to the construction of the body of a can of the type which is provided with a hinge pintle for the lid.

15 The particular object of the invention is to provide a method and apparatus for constructing can bodies whereby the blanks may be automatically fed and the hinge pintles for the lid may be thereafter applied 20 at a point between the feeding operation for the body blanks and the operation of forming the body. In explanation of this object it might be said that while, in the formation of can bodies by machines now on the 25 market, it has been common to apply the hinge pintles before the operation of forming the body, in such machines it is necessary to feed the blanks with the pintles thereon to the body forming mechanism by 30 hand for the reason that such pintle-equipped blanks cannot be handled by the automatic feeding devices employed in machines of this character; further, that it has also been common to automatically feed the 35 blanks to notching devices to form the pintle knuckles and thereafter to the body forming mechanism, the pintles being afterwards applied by a separate mechanism. By my improved method and apparatus, I am enabled 40 to employ the automatic feeding devices for the blanks and then automatically convey them to notching, pintle applying and body forming devices which are all embodied in a single machine so that the completed can 45 body will issue from the machine with the pintle applied.

A further object of the invention is to devise a pintle applying mechanism of simple and effective construction, one of the features thereof being that it is so arranged that 50 the wire forming the pintles may be fed in a line transversely to the travel of the body blanks, permitting the pintle to be applied to the forward edge of the blank so as to 55 leave the side edges free to be flanged later,

by the body forming mechanism, and also resulting in greater accuracy in the application of the pintles to the blanks for the reason that any variation in feed would have the effect only of applying the pintles at a greater or less distance from the top edges 60 of the bodies, whereas if the pintles were applied at the sides, considering the direction of travel, variation in feed would cause the pintles to be applied at varying points in the widths of the bodies, making it difficult or impossible to afterwards properly apply the lids. 65

In the accompanying drawings:—

Fig. 1 is a top plan view of a body forming machine embodying the improved pintle applying devices. 70

Fig. 2 is a vertical section on the line 2—2 of Fig. 1.

Fig. 3 is a side view of the pintle applying devices showing the same in operated position. 75

Fig. 4 is an end view of the same, showing the parts in inoperative position.

Fig. 5 is a vertical section on the line 5—5 of Fig. 4, with the parts in inoperative position. 80

Fig. 6 is also a section on the line 5—5 of Fig. 4, but showing the parts in operated position. 85

Fig. 7 is a top plan view of the platen or block upon which the blank rests as the pintle is being applied.

Fig. 8 is an enlarged detailed section of a portion of the machine, the section being 90 on the line 8—8 of Fig. 1.

Fig. 9 is a top plan view of a portion of the can body blank showing the same after the notching operation which forms the knuckles for the pintles. 95

Fig. 10 is a view of the same part of the blank after the application of the pintle.

Fig. 11 is a section on the line 11—11 of Fig. 10.

Fig. 12 is a bottom plan of the pintle applying head. 100

Fig. 13 is a top plan, partly in section, of the wire feed devices.

Fig. 14 is a section on the line 14—14 of Fig. 13. 105

Fig. 15 is a detail of the same.

Fig. 16 is a view of the forward end of the machine.

All of the operating parts of the machine are mounted upon a table 1. At the for- 110

ward end of this table is located the automatic feed mechanism which has an inclined hopper 2 in which the body blanks in the form of metal sheets are vertically arranged. 5 This mechanism operates on the principle of the feeder described in Letters Patent No. 1,081,050 dated Dec. 9, 1913 to Peter Kruse in that it employs a suction device to carry the metal sheets one by one from the hopper 10 and deposit them upon supporting bars to be grasped by carrier bars which convey the same to the various operating mechanisms. The only substantial difference between the feeding mechanism shown in the 15 present case and that of the Kruse patent referred to is that the blanks are arranged in a vertical direction in the hopper 2 and are removed therefrom by the suction device 3 at the inner side of the hopper instead of 20 at the bottom; and, further, that there are employed on each side of the hopper a series of finely serrated rolls 4 which are revolved reversely to the direction of travel of the metal sheets and whose serrated faces engage 25 the side edges of the sheets and thereby separate the sheets to prevent feeding more than one sheet at a time. The rolls are driven from the shaft 19. This shaft 19 has at its forward end a gear 4^a which drives a gear 4^b which in turn drives a vertical shaft 4^d through the medium of a pair of beveled gears (not shown) mounted in a casing 4^c. This vertical shaft has its upper end geared 30 to a horizontal shaft 4^e provided with two beveled gears 4^f which mesh with beveled pinions 4^g connected respectively with the rolls 4. The suction device 3 which is in the 35 nature of a cup, is mounted at the upper end of an arm 3^a the lower end of which is connected with a sleeve 3^b mounted upon a stud whose head is indicated at 3^c and which is journaled in a bearing 3^d. The sleeve 3^b has connected therewith a rod 3^e the lower end of which is connected to a crank arm 3^f 40 on the end of a shaft 3^g, this shaft being geared to the shaft 4^d through the medium of beveled gears (not shown) located in the casing 3^h. Suction is created in the suction device 3 through a pump 3ⁱ whose piston rod 50 3^j is connected with an eccentric pin 3^k on the gear 4^a. The pump is connected with the suction device through the pipes 3^m, hollow stem 3ⁿ leading to the sleeve 3^b and arm 3^a which has a passageway therein. 55 Each blank is deposited by the suction device, which swings upwardly and downwardly on the arc of a circle, upon the forward ends of a pair of supporting bars 5, and its rear edge is engaged by hooks 6 on the forward end of reciprocating carrier bars 7, arranged between the bars 5 and guide bars 8 which lie above the same. The blank, as the carrier bars reciprocate rearwardly, is carried beneath the upturned ends 60 of keeper strips 9 located above but spaced

slightly apart from the supporting bars 5. The bars 7 are provided at suitable intervals throughout their length with spring-pressed fingers 7^a, which, as the bars reciprocate, engage the rear edge of the blank and carry 70 it rearwardly to proper points to be operated upon by the various mechanisms, these fingers, as the bars reciprocate forwardly, yielding so as to ride under the blank. This carrying mechanism is very similar to that described in the Kruse patent referred to and also in some of his later patents which will be hereinafter referred to; the bars being operated by suitable devices (not shown) to impart a reciprocating movement 80 thereto.

As the carrier bars reciprocate rearwardly they carry the forward edge of the blank (considering its direction of travel) beneath the punching mechanism which operates to 85 punch the blank in the manner shown in Fig. 9 to form thereon tongues. The punch 12, (see Fig. 8) is connected to a slide 13 mounted in gibs 13^a carried in recessed arms 14^a of a yoke shaped support 14, and the punch co-operates with a die 15 on the table 1 to punch the blank in the manner before described. The slide is pivotally connected through a rod 16 with the bifurcated end of 90 a rocker arm 17 pivoted on a pin 17^a on the support 14, the other end of which is pivotally connected to the rod 18 (Figs. 1 and 2), the lower end of which is forked and straddles the cam shaft 19, having a cam 20, which cam has an operative connection 95 with a cam roller (not shown) on the rod 18.

After the punching operation, certain of the fingers 7^a on the bars then carry the blank to the pintle applying mechanism where a pintle is secured thereto in the manner shown in Fig. 10. This pintle applying mechanism is carried at the lower end of a slide 22 (Fig. 8) mounted in gibs 23 carried by one of the arms 14^a of the support 14 connected with the rocker arm 17 through the rod 16 previously referred to. Secured to the lower end of the slide by the bolt 24 is a head 25. Slidably mounted in this head 25 are two transversely extending rows of wire guide 115 pins 26. Adjacent pins of the respective rows have their upper ends reduced and extended into a guide plate 27 which is slidably mounted in a chamber 28 in the head, and interposed between this guide plate and the upper end of a recess 29 in the slide is a spring 30 which normally projects the pins downwardly to the position shown in Figs. 4 and 5. The lower face of the head is provided with a longitudinally extending grooveway 31, a part 120 of which is divided by a wall 25^a as indicated in Fig. 12. Slidably mounted in this groove and held therein by a keeper plate 32, secured to the head by the screw 33, is a plunger 34. This plunger has an elongated opening 130

to accommodate the screw 33 and also a recess 36 to accommodate the wall portion 25^a. Its rear portion has a square opening 36^a separated from the extreme end thereof by a 5 rounded cross-piece 37 which is designed to operate in an inclined groove 38 of an operating member 39. This operating member 39 is slidably mounted in a guide 40 (see Fig. 2) and is projected upwardly and downwardly 10 therein from a cam 41 on the cam shaft 19 through the medium of a rod 42, which carries at its lower end a roll (not shown) co-operating with the cam and is connected to the operating member 9 by the pivoted link 43 and ear 44.

Before the operation of the pintle applying devices thus far described, and just before the blank has come to rest beneath the applying devices, a length of wire to form 15 the pintle is fed to position between the blank and the head 25. The wire feeding devices are illustrated in Figs. 1, 2, 13, and 14. The wire may be mounted upon a reel (not shown) and first passes through a tension device (Fig. 1) consisting of a pair of wooden blocks 45 held together by adjustable clamps 46 carried by the support 47. From the tension device the wire projects through a feeder consisting of a head 48 having a channel 20 through which the wire passes and a slot 48^a within which is located a clutch member 50, pivoted on the pin 49 and having a rounded clutching face 51 which swings in a recess 52, formed on the arc of a circle and which communicates with the wire channel so as to allow the clutching face to engage the wire. The head 48 preferably has a hardened pin 53 inserted therein formed with a V-shaped 25 notch 54 in line with the wire channel in the head. The head 48 is preferably integrally formed with the upper end of a rocker arm 55 pivoted to a bracket 56 and having its lower end connected to a rod 57 which carries a cam roller (not shown) co-operating 30 with a cam 58 on the cam shaft 19 so as to impart transverse rocking movements to the head.

Means are provided for causing the clutch dog 50 to engage the wire to feed the same only at such times as blanks are being fed through the machine. At a proper time the end of a rod 59 is projected into the path of the tail 50^a of the clutch by a finger 60 coming in contact with a blank (Fig. 1) rocking shaft 61, having a crank arm 62, to which is pivoted the connecting rod 59. If no blanks are passing through the machine, a spring 63, interposed between a collar 64 on the rod and the support 47 through which the rod 59 45 extends, projects the rod out of the path of the tail 50^a, rocking the shaft 61 and dropping the finger 60 to a position to be raised by any oncoming blank.

Also interposed in the path of the tail 50^a 50 is an adjustable stop 65 in the nature of a

screw threaded in a lug on the support 47; this stop being so positioned as to disengage the clutch from the wire as soon as the proper length of wire has been fed to form a pintle.

As the feed mechanism operates to feed the wire, the end of the wire is projected between the rows of pins 26 to proper position above the punched out portion of the blank, the pins forming a guideway for the wire. Carried at the side of the head 25 is a cutter 70 in the form of a pivoted arm 66 (Figs. 3 and 4) which is normally projected downwardly by a spring 67; the downward movement being limited by a pin 66^a (Fig. 3). This arm has an aperture 68 through which the wire 75 extends and in which the wire always remains. As the head now descends, this cutter, striking the blank 3 which is being supported by a die block 69, moves upwardly and co-operates with the lower edge of the 80 head to shear the wire. The head has now descended to a point to force the cut-off portion of the wire onto the blank just above a groove 70 in the die block which forces the metal of the blank into the groove, thereby 85 slightly raising the ends of the tongues b; the under surface of the head having grooves 25^b to receive and centralize the wire, as shown in Fig. 12. These tongues lie in the path of movement of the plunger 34 and as this plunger 90 is now operated by the operating device 39, the tongues will be bent over the pintle in the manner shown in Fig. 10, with the ends of the pintle resting upon the blank at the respective sides of the cut-out portion. 95 A spring 71 (Fig. 3) serves to hold the plunger 34 in inoperative position.

From the pintle applying mechanism, the blanks are carried to the body forming mechanism, where the side edges of the 100 blanks are first formed with hook-shaped flanges and then bent about a former, the hooks interlocked and then clinched. This body forming mechanism has been indicated in a general way by the reference character 105 C and is of a well known construction, being shown in the Kruse patent previously referred to and also in the following patents of the same inventor: Nos. 1,129,302 dated Feb. 23, 1915; 1,135,534 dated Apr. 13, 1915; 1,242,206, dated Oct. 9, 1917; 1,244,056 dated Oct. 23, 1917.

A brief description of the operation is as follows:

The blanks are fed one by one by the automatic feeding mechanism, being deposited upon the bars 5, along which and beneath the keeper strips 9 they are intermittently carried by the reciprocating carrier bars 7, first to the notcher, then to the pintle applying mechanism and then to the body forming mechanism. The operation of feeding the wire is performed during the carrying movements of the blanks so that a length of wire is in position to be severed and applied 110 115 120 125 130

so soon as a notched blank has been fed to proper position for the pintle applying operation. A succeeding blank has also been fed to position beneath the notcher, and, during the interval of rest of the blanks as the carrier bars are reciprocating forwardly, the operations of notching and pintle applying will be simultaneously performed. The wire feeding devices have now returned to initial position so that after the notching and pintle applying operations have been completed, the carrier bars again reciprocate rearwardly and a new length of wire is fed by the feeding devices.

15 By the constructions described, it will be seen that the can bodies when discharged from the machine are equipped with pintles to form hinges for the lids which are afterwards applied by a separate operation. Inasmuch as the pintle applying mechanism operates simultaneously with the punching mechanism, it requires no additional time to apply the pintles, so the capacity of the machine, by reason of this additional pintle applying operation, is not therefore decreased. By the specific arrangement of pintle applying mechanism including the wire feeding devices, I am enabled to apply the pintles upon the forward edge of the blanks, considering the direction of travel, thereby permitting the blanks to be fed directly in a straight line to the body forming mechanism of the machine, the arrangement of which is such that the blanks are flanged upon their side edges.

20 Further, by reason of the fact that the pintles are applied upon the forward edges of the blank any slight variation in the feed of the blanks and consequent variation in the position of the pintles will have no appreciable effect so far as thereafter properly applying the lids to the bodies is concerned, as any such variation would only result in the application of the pintles in positions more or less slightly removed from the upper edge of the bodies, whereas in machines which apply the pintles at the sides of the blank, considering the direction of travel, variations in feed would result in variations in the positions of the pintles in relation to the width of the bodies, thus making the subsequent application of the lids difficult and in some cases impossible.

25 Having thus described my invention, I claim:

1. The method of applying pintles to can body blanks consisting in automatically feeding blanks one by one, punching the blanks on their forward edges with relation to their direction of travel to form pintle knuckles and then applying pintles to the knuckle portions of said blanks.

2. The method of applying pintles to can body blanks consisting in automatically

feeding blanks one by one, punching the blanks on their forward edges to form pintle knuckles, feeding wire transversely across the knuckle portions of the blanks and thereafter severing the wire and securing the severed portion to the blank by a bending operation of the knuckles.

3. In a machine for attaching wire pintles to metal receptacles, the combination of means for intermittently feeding metal blanks in a straight path through the machine, wire feeding means arranged to feed the wire transversely to the path of movement of the metal blanks, and means for securing the severed portion of the wire to the blank for forming a pintle thereon.

4. In a machine for attaching wire pintles to metal receptacles the combination of a hopper having plain metal blanks therein, automatic means for feeding same from said hopper and transmitting same by an intermittent feeding motion, means for cutting notches and forming knuckles on the edges of same during said intermittent feeding movement, means for feeding wire to said notched blanks in a path transversely to the path of movement of the blank, means for cutting pintles from said wire, and means for attaching the pintles to the notched blank.

5. In a machine of the character described, blank carrying mechanism, and pintle applying devices arranged to apply a pintle to an edge of a blank which lies at right angles to its direction of travel.

6. In a machine of the character described, blank carrying mechanism, and pintle applying devices arranged to apply a pintle to the forward edge of a blank considering its direction of travel.

7. In a machine of the character described, blank carrying mechanism, and pintle applying mechanism for applying pintles to the forward edges of the blanks, including wire feeding devices for feeding wire transversely to the direction of travel of the blanks.

8. In a machine of the character described, pintle applying mechanism, and wire feeding devices for the same, said mechanism having a plurality of yieldable wire guides arranged in rows.

9. In a machine of the character described, pintle applying mechanism comprising a slid able head, a plurality of wire guides arranged in two rows normally yieldably projected below said head, and wire feeding devices associated with said head.

In testimony whereof I have hereunto set my hand this 4th day of February, 1921.

JAMES T. TAYLOR.

Witness:

CHAS. I. WELCH.
